FEELER MECHANISM FOR LOOMS

Arthur E. Benson, Dedham, Mass.

Application March 14, 1933, Serial No. 660,627

6 Claims. (Cl. 139—283)

This invention relates to feeler mechanism for looms whereby the operative condition of the loom is changed from time to time, and is more particularly concerned with feeler mechanisms of the side slipping type which become displaced by the forward pressure of a surface within the shuttle when the filling becomes substantially exhausted.

Feeler mechanisms of the side slipping type are not new and various expedients have been devised and associated with side slipping feelers to bring about a change in the loom operation, such for instance as replenishment of filling or loom stoppage.

15 Sensitiveness of the feeler either to the presence or substantial absence of filling in the shuttle is a most important factor for the economic running of looms and where the feeler mechanism functions to initiate replenishment of filling, the amount of waste left upon a filling carrier or bobbin will depend upon the response of the feeler when the filling becomes substantially exhausted. Where the feeler initiates loom stoppage any failure of the feeler to respond to substantial

25 absence of filling may result in imperfect cloth.

One of the objects of the present invention is to provide a feeler mechanism of the side slipping type which shall be simple in construction and effective in operation either to effect loom stoppage on substantial exhaustion of filling or initiate filling replenishment and in case the loom is to be stopped, it is a further object of the invention that such stoppage shall be effected after the depleted shuttle is returned to the detecting box.

The invention and novel features thereof will best be made clear from the following description and accompanying drawings of one good form thereof.

40 In the drawings:—

Fig. 1 is a perspective view showing the feeler mechanism of the present invention associated with a loom, some of the parts being broken away for clearness of illustration;

45 Fig. 2 is an enlarged plan view showing the relation of parts when the feeler detects a working supply of filling in the shuttle on a detecting beat;

Fig. 3 is a view similar to that of Fig. 2 showing the feeler as having detected a substantial exhaustion of the filling on a detecting beat;

Fig. 4 is a sectional elevation showing the relation of parts when the feeler has detected a substantial exhaustion of filling on a detecting beat;

55 Fig. 5 is a section on the line 5—5 of Fig. 3; and

Fig. 6 is a section on the line 6—6 of Fig. 5.

In the present instance the invention will be described in connection with loom stopping mechanism to bring the loom to rest when the depleted shuttle has returned to the detecting box.

The loom frame 1 may be of any usual desired construction and suitable for the support of the operating parts, and having a shipper stand 2 provided with a slot 3 in which the shipper 4 may move outwardly when the loom is to be stopped. A shoulder 5 normally holds the shipper 4 in loom running position, but when the shipper is detached from the shoulder 5 it will move to loom stopping position and finally bring the loom to rest.

Secured to the shipper stand 2 is a bracket 6 for the support of the feeler stand 7 on which is pivotally supported at 8 a swinging arm or carrier 9, and pivotally connected to the swinging arm or carrier 9 at 10 is the side slipping feeler 11, the rear end of which is provided with a roughened surface or teeth 12 for engagement with the filling or bobbin within the shuttle on a detecting beat.

Surrounding the pivotal axis 8 on the swinging arm or carrier 9 is a spring 13, one end of which is secured to the feeler stand as at 14 and the other or free end of which 15 is connected to the feeler, the construction being such that the spring 13 normally acts to move the swinging arm or carrier 9 and the feeler rearwardly to feeling or detecting position as indicated in Fig. 1.

As is more clearly indicated in Figs. 5 and 6 the swinging arm or carrier 9 has a recessed portion 16 on its under surface in which the head 17 of a spring engaging member may be received and travel as the feeler moves on its pivotal connection 10 with the swinging arm or carrier 9. The depth of the recessed portion 16 is such that the end portion of the spring 15 is prevented from riding up or over the head 17 of the spring engaging member, so that a simple yet effective construction is provided for maintaining the end of a spring 15 in operative engagement with the feeler.

The spring engaging member may be conveniently formed as a headed screw 18 and in order that the end 15 of the spring 13 may be caused to exert more or less energy upon the feeler and thereby regulate its sensitiveness the headed screw 18 is adapted to be received in any one of the openings 19 formed in the elbow portion of the feeler.

Mounted on the feeler stand 7 is a stop 20, Figs. 4 and 5, which may engage the downwardly extending portion of the pivotal mounting 10 of

the feeler to limit the rearward movement of the swinging member or carrier 9 and the feeler.

The lay 21 may be of usual construction and is provided with the detecting shuttle box 22 the 5 front wall 23 of which has an opening 24 adapted to register with a corresponding opening 25 in the front wall of the shuttle 26 when the latter is in the detecting box, with the result that on the detecting beat the feeler will enter the register- 10 ing slots and be permitted to detect the condition of the filling in the shuttle on a detecting beat.

Mounted on the lay is a bunter 27 having a rounded upper surface 28 and a notch 29 for operative engagement with an actuator, presently 15 to be described, for actuating the shipper knock-off. Pivotal mounted at 30 on the shipper stand is the shipper knock-off 31, the outer end portion of which bears against the side of the shipper 4 when the latter is in running position, 20 and pivotally connected to the shipper knock-off at 32 is the shipper knock-off actuator 33 having a slot 34 which is engaged by an arm 35 of a transmitter between the feeler and the actuator.

The transmitter, designated as a whole A, has 25 a rearwardly projecting finger 36 and cooperating with the finger 36 of the transmitter is the tail portion 37 of the feeler, the construction being such that when the feeler is in loom running position, as indicated in Figs. 1 and 2, the finger 36 will rest upon the tail 37 of the feeler, thereby holding the actuator 33 in its upward or inoperative position.

The transmitter A is preferably formed of two members, one of which as 38 carries the finger 36 and the other member 39 of which carries the arm 35 which engages the actuator 33.

The two member construction of the transmitter lends itself favorably to separate or independent adjustment of the two members thereof, 40 so that the arms 35 and 36 may be properly associated with their cooperating parts.

In order that the transmitter may have its two members integrated or connected, the two members 38 and 39 are joined by a connection 40 carrying the lugs 41 and 42 to which the two members of the transmitter are secured by binding screws 43.

The transmitter member is mounted for rocking movement in the lugs 44 and 45 extending 50 from the shipper stand and since the connector 40 extends laterally from the longitudinal axis of the transmitter, such connection acts as a weight normally tending to turn the transmitter in a contra-clockwise direction with the finger 36 resting upon the tail 37 of the feeler to maintain the actuator 33 in its upward or inoperative relation with the bunter 27.

From the construction thus far described it will be apparent that on each detecting beat of the 60 lay, the feeler will enter the shuttle in the detecting box and feel for the filling. If a working supply of filling is present the feeler will be subjected to a forward push while its teeth 12 may sink into or engage the filling with non-slipping 65 contact and the swinging arm or carrier 9 will be moved forwardly with the feeler while the tail 37 of the feeler still maintains the transmitter in position with the actuator 33 in upward or inoperative position. Should, however, the feeler 70 detect a substantial exhaustion of filling in the shuttle it will side slip, as indicated in Fig. 3, under the forward push of the bobbin as the lay beats and the tail 37 of the feeler will be moved laterally, as indicated in Fig. 3, to thereby position the finger 36 for downward movement as the transmitter

rocks contra-clockwise under the action of the connector 40. At this time, however, the lay will have substantially reached its forward position or will be closely approaching such position and the actuator 33 will drop upon the top surface of the bunter, as indicated in Fig. 4. This drop movement is permitted by reason of the fact that the slot or opening 34 in the actuator is sufficiently wide to permit the arm 35 of the transmitter to move downwardly in the slot and thereby free the actuator to downward movement into engagement with the top of the bunter.

With the parts in the position last described after detection of substantial exhaustion of filling, 80 the lay will move back, the shuttle in the detecting box be picked to the opposite shuttle box, and as the lay moves back the actuator 33 will drop off of the top of the bunter into operative position as indicated by dotted lines in Fig. 4, so that on the next beat up movement of the lay with the shuttle in the non-detecting box, the bunter will engage the actuator and cause forward movement thereof, with the result that the shipper knock-off will be actuated to detach the shipper 95 from its holding notch and permit the shipper to move to loom stopping position. The momentum of the loom parts after the shipper has been moved to stopping position and the lay moves back again will cause the shuttle to be returned to the detecting box and the loom will come to rest with the 100 denuded shuttle in the detecting box where it may be removed by the loom attendant, and a fresh filling carrier inserted.

When the finger 36 is freed from engagement with the tail 37 of the feeler, the finger will drop 110 as indicated in Fig. 3, and thereafter act to hold the feeler in its side swiped position.

In accordance with the present invention resetting means is provided to reset or move the actuator into its inoperative position and permit the 115 tail 37 of the feeler to again underlie the finger 36 of the transmitter.

In the present instance of the invention the transmitter has a resetting toe 46 secured thereto and extending forwardly from the transmitter, 120 while the shipper 4 is provided with a lug or projection 47 so that as the shipper moves to its loom stopping position the projection 47 of the shipper will engage the resetting lug 46 of the transmitter and turn the transmitter clockwise viewing Fig. 1, 125 thereby resetting the feeler mechanism into loom running position, so that after the correction of the fault in the shuttle the loom attendant has simply to move the shipper from its stopping to its running position and the loom will at once 130 respond and weaving be continued.

What is claimed is:—

1. In a feeler mechanism for looms, the combination of the lay having a bunter, a shipper knock-off actuator adapted to be operated by the bunter 135 on the lay, a side slipping filling feeler having a forwardly extending tail portion, a transmitter connected to the actuator and having a projection to rest upon the tail of the feeler and hold the actuator out of operative position until the feeler 140 side slips on a detecting beat and thereupon permitting the actuator to drop onto and be supported by the bunter and thereafter to move into operative position relative to the lay carried bunter as the lay goes back and be actuated on the 145 next beat up of the lay to effect loom stoppage with the shuttle in the detecting shuttle box.

2. In a feeler mechanism for looms, the combination of the lay having a bunter, a shipper knock-off actuator adapted to be operated by the 150

5	bunter, a side slipping filling feeler having a frontwardly-extending tail portion, a transmitter connected to the actuator and having a projection to rest upon the tail of the feeler and hold the actuator out of operative position until the feeler side slips on a detecting beat and thereupon permitting the actuator to drop off the bunter and move into operative position as the lay goes back and be actuated on the next beat up of the	80
10	lay to effect loom stoppage with the shuttle in the detecting shuttle box, and means actuated by the shipper movement to stopping position to reset the transmitter and feeler.	85
15	3. In a feeler mechanism for looms, the combination of the lay having a bunter, a shipper knock-off actuator adapted to be operated by the bunter, a side slipping filling feeler having a frontwardly extending tail portion, a transmitter connected to the actuator and having a projec-	90
20	tion to rest upon the tail of the feeler and hold the actuator out of operative position until the feeler side slips on a detecting beat and thereupon permitting the actuator to drop off the bunter and move into operative position as the lay goes	95
25	back and be actuated on the next beat up of the lay to effect loom stoppage with the shuttle in the detecting shuttle box, a resetting lug extending from the transmitter and a part actuated by shipper movement to stopping position to en-	100
30	gage the resetting lug to turn the transmitter to initial position.	105
35	4. In a feeler mechanism for looms, the combination of a feeler stand, a link pivotally mounted on the feeler stand, a side slipping filling feeler pivotally mounted on the link and having a frontwardly extending tail, a shipper and shipper knock-off, an actuator connected to the shipper knock-off, a bunter on the lay for operating the actuator to effect loom stoppage, a transmitter	110
40	connected to the actuator and having a projection normally resting on the tail of the feeler to	115
